UNITED STATES PATENT OFFICE.

WILLEBALD C. STENGER, OF CHICAGO, ILLINOIS.

CUTTING-TOOL FOR WOOD-CARVING MACHINES.

1,330,287.

Specification of Letters Patent. Patented Feb. 10, 1920.

Application filed June 6, 1918. Serial No. 238,489.

To all whom it may concern:

Be it known that I, WILLEBALD C. STENGER, a citizen of the United States, and a resident of Chicago, in the county of Cook and State of Illinois, have invented certain new and useful Improvements in Cutting-Tools for Wood-Carving Machines; and I do hereby declare that the following is a full, clear, and exact description thereof, reference being had to the accompanying drawings, and to the letters of reference marked thereon, which form a part of this specification.

This invention relates to improvements in cutting tools for wood carving machines and consists of the matters hereinafter described and more particularly pointed out in the appended claims.

The object of the invention is to provide an efficient rotary cutting tool for use in wood carving machines, which may be easily made and sharpened, and which is of such shape as to operate to the best advantage on flat work as well as work of other forms. Another object of the invention is to provide a cutting tool which will act to leave a clean cut and burnished surface, thus eliminating the necessity of again operating upon the wood for the removal of cutter marks. These objects as well as the several advantages of my invention will be more apparent as I proceed with my specification.

In the drawings:

Figure 1 represents a perspective view of a rotary cutting tool embodying my invention, as observed from the front or cutting edge side thereof.

Fig. 2 represents a view in side elevation of the tool as it would appear when turned a quarter of a revolution from the position shown in Fig. 1.

Fig. 3 represents a view in rear elevation of the tool as it would appear when turned a half of a revolution from the position shown in Fig. 1.

Fig. 4 represents a horizontal sectional view through the tool, the plane of the section being indicated by the line 4-4 of Fig. 1.

Fig. 5 represents a bottom plan view of the cutting tool.

Referring now in detail to that embodiment of my invention illustrated in the accompanying drawings:—10 indicates the

tool as a whole which comprises a shank 55 11 and a cutting head 12 formed at one end of said shank. The shank 11 in this instance is shown as cylindrical, but as is apparent, said shank may be made in other shapes to fit the particular tool-holding chuck with 60 which it is used.

The bottom end of the shank 11 is gradually flattened upon opposite sides to provide a tapering neck 13, which is twisted spirally about the axis of the shank as a 65 center for a short distance, after which it is bent into a plane at substantially a right angle to the shank to form a semi-cylindrical flange member 14. This flange member is concavo-convex, with its convex bottom 70 surface 15 substantially approximating a part of a sphere, although its contour may be somewhat varied.

The flange member 14 terminates in a bevel edge 16 which extends radially from 75 the axis of the shank and which is beveled on the top side of the flange member to provide the sharpened cutting edge 16^a of the tool head. As is apparent from the drawings, this cutting edge is of a length, equal 80 to the radius of the flange member 14 and of course assumes the curvature thereof.

The operation of the tool when used in connection with the rotating chuck of a carving machine, is as follows. The work 85 piece to be operated upon is moved into a suitably operative position to be operated upon by the tool, which may be rotated by any suitable means. The work is advanced toward the tool and the cutting edge 16^a 90 cuts away that part of the work in its path, in the form of small chips or shavings which are directed upon the flange member 14. Under the centrifugal action of the rotation of the tool, these chips are thrown or 95 deposited a distance away from that part of the work just previously engaged by and also that part of the work in advance of the cutting edge of the head, thus in no way obliterating such pattern lines as are to be 100 followed upon the work.

As the cutting edge 16^a removes the chips, that part of the convex bottom surface 15 immediately adjacent the cutting edge, will act to smooth and burnish that part of the 105 work just operated upon to provide a smooth edge in which all of the pores of the wood will be closed. By reason of the shape of the

cutting head, I am enabled to operate upon flat work as well as work of other shapes, and I am also enabled to use said tool as a "gouge," thus being able to follow form patterns such as scrolls, etc.

5 My improved tool acts to throw the chips or shavings clear from itself and from the work, thus it can never become clogged. The tool may be easily sharpened and it may 10 receive a great many sharpenings before its efficiency as a tool for its intended purpose is changed or destroyed.

The improved tool is capable of efficient 15 operation at a substantially slow speed when compared with other tools for a like purpose, which must be driven at a high speed.

20 While in describing my invention I have referred to certain details of construction and arrangement of parts, I do not wish to be limited thereto except as may be pointed out in the appended claims.

I claim as my invention:

1. A cutting tool comprising an integral 25 head and shank, the shank being flattened on opposite sides to form a neck tapering toward the head, the head comprising a concavo-convex flange member extending in a plane substantially at right angles to the axis of the shank and terminating in a

sharpened cutting edge extending radially 30 to the shaft.

2. A tool of the kind described, comprising a shank and a head, said head consisting of a concavo-convex flange member arranged substantially at right angles to said shank, 35 said flange member being about 180° in arcuate length and terminating in a sharpened cutting edge arranged radially of said shank.

3. A tool of the kind described, comprising a shank and a head, said shank being flattened on opposite sides to form a tapering neck, which is twisted into a radial, concavo-convex flange member arranged substantially at right angles to said shank, said 45 flange member being 180° in arcuate length and terminating in a radial edge which is sharpened on its top side to form the cutting edge for said head.

In testimony, that I claim the foregoing 50 as my invention I affix my signature in the presence of two witnesses, this 29th day of May A. D. 1918.

WILLEBALD C. STENGER.
